UNITED STATES PATENT OFFICE.

RENÉ FRANÇOIS CHARLES RAMBEAUD, OF PARTHENAY, FRANCE.

BEATING AND KNEADING MACHINE.

No. 913,766.

Specification of Letters Patent.

Patented March 2, 1909.

Application filed September 17, 1907. Serial No. 393,372.

To all whom it may concern:

Be it known that I, RENÉ FRANÇOIS CHARLES RAMBEAUD, a citizen of the French Republic, and resident of Parthenay, Deux-Sèvres, France, have invented a certain new and useful Beating and Kneading Machine, of which the following is a specification.

The object of the invention is to provide a novel machine for beating the glair of eggs, for beating biscuits, mayonnaise, and the like, and for kneading soft or hard pastes by means of interchangeable beating and malaxing members, which machine shall be simple of construction, thoroughly efficient in operation, and durable in use.

In the annexed drawing given by way of example: Figure 1 is a side elevation view of the above machine arranged for one application. Fig. 2 is a front elevation view. Fig. 3 is a detail view partly in section, partly in elevation of same. Fig. 4 is a side elevation view of the machine arranged for a second application. Fig. 5 is a front elevation view of the beating member adapted to serve for this application. Fig. 6 is a detail view of a whip carrier. Fig. 7 is a detail view of a beater. Fig. 8 is a detail view of a different form of beater. Fig. 9 represents a beating member adapted to be used in connection with another application of the machine. Fig. 10 is a detail view of a modification of certain parts shown in Figs. 1 and 2. Fig. 11 is a detail view of a modification of certain parts shown in Fig. 9.

The machine shown in Figs. 1 to 3 comprises a framework 1 upon which is mounted a shaft carrying a large toothed wheel 2 and a driving fly-wheel 45 the said toothed wheel driving a small spur pinion 3 which by means of a flexible shaft 4 transmits a rapid rotary motion to a small bevel pinion 5 mounted on the movable arm 6 of the bracket 7 secured by two tightening struts and by a nut 82 to a ring 27. This small pinion 5 drives the bevel 8 which is movable on the shaft 9 (Fig. 3) secured to the head of the arm of the bracket 6 by means of the nut 10 which also allows of the ball bearing 11. The suspension member 12 having the form of a stirrup carries by means of the two trunnions 13 a ring 14 which is itself provided with two poles 15 perpendicularly arranged to the axis of the trunnions and wherein a pin is engaged which crosses the upper end of the shaft 16 of the beating member which has any desired form. The arm 6 may be fixed

at the desired height on the standard 7 by means of a pressure screw 42.

The shaft of the beating member or beater passes through the ring 17 of the great lever arm 18 the axis 19 of which is made integral with the bevel wheel 8. A spring 21 has a tendency to move away from the center the long arm 18 which is then adapted to apply the beater 16 upon the wall of the basin 22 while the small arm 20 of the said lever which passes through the wheel 8 abuts against an eccentric 23 (Fig. 3) made integral with a toothed wheel 24 which is mounted upon the bevel wheel 8 and meshes with a small spur pinion 25 which is itself made integral with the shaft 9.

The ring 27 mounted on the shaft 29 is adapted to take different inclinations during the operation of the machine by means of the toothed sector 30 driven by the worm 31 and by the small crank 32. Upon the said ring 27 is secured the standard 7 carrying the above cited beating system and which follows the inclination of the said ring. On the said ring also reposes by the intermediary of a ball bearing system, a second toothed ring 28 which may have the form of a bevel wheel 28' (see Fig. 10) and in this case is rotated by a conical pinion 33' (Fig. 10). The ring 28 (Figs. 1 and 2) may also have a helicoidal toothing 28 and be actuated by a worm 33 driven by a flexible shaft 37 (Fig. 1). This second ring is held on the ring 27 by means of the small rollers 34 the pressure of which is controlled by means of the screws 35. This ring 28 receives the basin 22 containing the products to be beaten and carries it on with it in its rotary motion transmitted thereto by the worm 33, the flexible shaft 37 and the small pinion 38 mounted upon a movable member 39 held in mesh with the big toothed wheel 2 by the spring 40 secured to the arm 41 of the framework 1; it is consequently possible to remove the pinion 38 from the wheel 2 in order to render the ring 28 and the basin stationary.

Secured to the standard 7 is a stud 86 upon which is adapted to oscillate an arm 84 carrying a scraper 43 which may be applied by a spring 85 against the inner wall of the basin 22.

This apparatus works as follows: Movement of the fly-wheel 45 rotates the wheel 2 and, through the intermediate mechanism, causes the beater to travel around the interior sides of the basin. The eccentric 23, in

tegral with the wheel 24, intermittently engages the lever-arm 20, which rocks the beater-arm 18 with the beater toward the center of the basin. As soon as the eccentric 5 leaves the arm 20, the spring 19 returns the lever to normal position. In this manner, the beater reaches all parts of the basin, in the similitude of hand-beating, and by my peculiar mechanism the high speeds used in 10 other beaters may be dispensed with and a better product obtained. The scraper 43 acts, with gentle pressure, upon the inner walls of the basin, to return the preparation to the center thereof, rendering the beating 15 operation perfect.

It may be advantageous especially for genooses and biscuits to raise the paste in order to aerate it and to render it lighter. With a view of securing this result the pressure screw 42 which secures the arm 6 to the standard 7 (Fig. 1) is loosened, the flexible shaft 4 is separated from the pinion 5 in order to remove the beating device: then the nuts 82 are unscrewed thus allowing of the standard 7 being shifted and secured on the studs 44 in a position wherein it is perpendicular with reference to its first position. Thus the standard instead of occupying the position shown by Fig. 2 may be placed in the 20 inclined position, shown by Fig. 4 when the whole ring carrying the basin oscillates around its axis 29. Then the sleeve 45 is slid on the rod of the said standard and secured thereto by means of the screw 47, this 25 sleeve carrying the beating device adapted to oscillate around the trunnion 46. This beating device comprises a member 48 having a suitable form and hollowed out part according to the dotted lines shown in the 30 drawings, so as to form two cheeks surrounding the sleeve 45'. One (50) of these cheeks has an opening 51 through which passes the screw 52 which is adapted to secure the device in the chosen position. The said member 45 carries two toothed wheels 53 having the same diameter and the same number of teeth, these toothed wheels being rotated in the same direction by the pinion 54 mounted upon the member 48 connected with the 40 flexible shaft 4. The two wheels 53 are provided with two radial openings 55 in which are adapted to slide the sliding members 56 which may thus be placed nearer the center of the said wheels 53 or farther away from 45 these centers. The trunnions of these sliding members 56 are connected by the rod 70 upon which slides the member 57 which is secured by means of the nut 58 at the desired height. The member 57 carries at its 50 end the whip carrier. The latter comprises a stud 62 (Fig. 5) made integral with a half collar 63 connected by a hinge 87 with another half collar 63' these two half collars being adapted to be held against one another 55 by a spring member 64 and then form a

chamber (Figs. 5 and 6) in which a yielding ring 65 is inclosed; through this ring passes the shaft 69 the beater of which is provided with an annular groove 68 adapted to be engaged by the two halves of the ring 66 which 70 holds the whole laterally while affording a certain suppleness. The whole is connected with the member 57 by means of a lug 62 having the form of a quadrant and by a pivot 60 so that the beater may receive any 75 desired inclination in which it is held by the tightening screw. This form of execution works in the following manner. The whole having been put in place, the screw 52 (Fig. 5) is loosened. Then by means of the worm 80 31 and of its toothed segment 30 (Fig. 3) the whole basin carrier 27 is inclined; the standard 7 then assumes the position shown by Fig. 4; the member 48 which is freely suspended by the trunnions 46 assumes a vertical position; then the nut 52 is tightened in order to secure the member 48 in position; then the ingredients necessary to the manufacture of the paste to be produced are poured into the basin, beginning with the 90 eggs or other liquid, the machine is then started whereby the flexible shaft 4 rotates the pinion 54 which actuates the two wheels 53; the rod 70 thus performs a vertical and circular motion; the beater 69 raises the 95 paste and causes it to fall again thus introducing therein a great amount of air which renders it frothy and light, giving a much greater output with a much lesser speed. The inclination of the machine may be varied during the work which is a great boon.

When a soft paste is to be produced such as a paste for light cakes, or for savarin, the member 57 is removed and replaced by the member 71 (Fig. 8) having a suitable shape, 105 the inclination of the basin being modified in such a manner that the rod descends in its center and with it the member 71 which has about the form of the recipient. This apparatus works in the following manner: During the work, the basin, while rotating slowly brings the paste under the member 71 which during its vertical and circular motion raises it and causes it to fall again just like the hand of the baker. The amplitude of the 110 motion of the rod 70 is varied by shifting forward or backwards the slide members 56 in their grooves and fixing them by means of the nuts 72 (Fig. 4).

When firm pastes are to be worked the 120 arm or bracket of the standard is replaced by that 73 shown by Fig. 9. This arm has a suitable form and carries a malaxating device composed either of a bevel wheel when the motion is transmitted by a bevel pinion 125 (Fig. 11) or of a helicoidal wheel 74 when the transmission takes place by means of a worm 75. On this wheel 74 are arranged two vertical shafts 78 provided with spirally arranged wings 80. Secured to these shafts 130

are two small pinions 76 adapted to receive motion from a third toothed wheel 79 secured to shaft 77 which is tightly secured to the top of the arm 73 by means of the nut 81. 5 For using the device the small pinion 38 (Fig. 2) is removed from the toothed wheel 2, if it is desired to render the basin stationary. The latter is then placed into the horizontal position (Fig. 1) 22; the malaxator is 10 then lowered into the basin or into a dish having a flat bottom; the liquid materials necessary for the preparation are then poured into the dish and afterward the other materials such as flour, butter and so on; the 15 machine is set going and by means of its flexible shaft the latter causes the wheel 74 (Fig. 9) to rotate through the intermediary of the worm 75; the shafts 78 which are carried by the said toothed wheel perform a 20 satellite motion around the shaft 77 owing to their pinions turning around the fixed pinion 79 and the wings 80 mix in a perfect manner the ingredients placed into the dish or basin.

The device shown by the Fig. 11 comprises a standard arm 89 having a suitable form and upon which is a screw 82 provided with a shoulder and adapted to serve as a shaft for the angle wheel 83 made integral with a small spur pinion 85 meshing with 25 two small spur wheels 86' and 86'' secured to the shafts 87 of the malaxators provided with helicoidal wings. The small bevel pinion 88 receiving its motion from the flexible shaft 4 transmits it to the bevel wheel 83 30 which carries on the other members of the device mixing thus in a most perfect manner the various ingredients disposed in the recipient.

Having now fully described my invention 40 what I claim and desire to secure by Letters Patent is:

1. In a device for beating eggs, etc., the combination with a frame, a basin pivotally suspended therefrom, means for inclining the basin on its pivot and for holding it at 45 any desired inclined adjustment, a member projecting into the basin for engaging the contents thereof, means for causing said member to travel around the interior sides of the basin, and means for causing said member intermittently to move toward and away from the center of the basin.

2. In a device for beating eggs, etc., the combination with a frame, a basin pivotally 55 suspended therefrom, means for inclining the basin on its pivot and for holding it at any desired inclined adjustment, a horizontally-disposed stationary ring encircling said basin, a second horizontally-disposed ring encircling said basin and resting on top of the stationary ring, a member engaging said second ring for rotating the basin, a member projecting into the basin for engaging the con-

tents thereof, and means for causing said member to travel around the interior sides 65 of the basin.

3. In a device for beating eggs, etc., the combination with a frame, a basin pivotally suspended therefrom, means for inclining the basin on its pivot and for holding it at 70 any desired inclined adjustment, a horizontally-disposed stationary ring encircling said basin, a second horizontally-disposed ring encircling said basin and resting on top of the stationary ring, means for holding said second ring against upward displacement, a member engaging said second ring for rotating the basin, a member projecting into the basin for engaging the contents thereof, and means for causing said member to travel 75 around the interior sides of the basin.

4. In a device for beating eggs, etc., the combination with a frame, a basin pivotally suspended therefrom, means for inclining the basin on its pivot and for holding it at 80 any desired inclined adjustment, a horizontally-disposed stationary ring encircling said basin, a second horizontally-disposed ring encircling said basin and resting on top of the stationary ring, rollers bearing against the 85 top of said second ring and supported from said stationary ring for preventing upward displacement of said second ring, a member engaging said second ring for rotating the basin, a member projecting into the basin 90 for engaging the contents thereof, and means for causing said member to travel around the interior sides of the basin.

5. In a device for beating eggs, etc., the combination with a frame, a basin pivotally 95 suspended therefrom, means for inclining the basin on its pivot and for holding it at any desired inclined adjustment, a member projecting into the basin for engaging the contents thereof, means for causing said member to travel around the interior sides of the basin, and a scraper operating within the basin.

6. In a device for beating eggs, etc., the combination with a frame, a basin pivotally 100 suspended therefrom, means for inclining the basin on its pivot and for holding it at any desired inclined adjustment, a member projecting into the basin for engaging the contents thereof, means for causing said member to travel around the interior sides of the basin, and a scraper operating within the basin, and a spring engaging said scraper for retaining the latter against the interior sides 105 of the basin.

In testimony whereof I have hereunto set my hand in presence of two witnesses.

RENÉ FRANÇOIS CHARLES RAMBEAUD.
